UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

SHUTTLE-BINDER FOR LOOMS.

SPECIFICATION forming part of Letters Patent No. 703,498, dated July 1, 1902.

Application filed January 2, 1902. Serial No. 87,990. (No model.)

To all whom it may concern:

Be it known that I, EDWARD S. STIMPSON, a citizen of the United States, and a resident of Hopedale, county of Worcester, State of Massachusetts, have invented an Improvement in 5 Shuttle-Binders for Looms, of which the following description, in connection with the accompanying drawings, is a specification, like characters on the drawings representing like parts.

When a loom stops, the shuttle is often partly in the shuttle-box, and before starting the loom the attendant must push the shuttle back into the box in order that the picker 10 shall properly coöperate with the shuttle.

In common looms, where the shuttles are frequently removed and replaced manually, the shuttle must always be pushed back into place in the shuttle-box by the attendant, and 15 in either case this has to be accomplished against the resistance of the binder and its strong controlling-spring. The binder is so located relatively to the cover or guard plate and wall of the shuttle-box that it is very difficult 20 for the operative to force the binder out of the shuttle-path with one hand while pushing the shuttle home with the other.

My present invention has for its object the production of simple means whereby the attendant 25 can readily retract the binder with one hand, clearing the shuttle-box, while he pushes the shuttle home with the other hand.

The novel features of my invention will be hereinafter described, and particularly pointed 30 out in the following claim.

Figure 1 is a top or plan view, partly broken out, of one end of the lay of a loom with the shuttle-box thereon with one embodiment of my invention applied thereto. Fig. 2 is a rear 35 elevation of the parts shown in Fig 1; and Fig. 3 is a perspective view, enlarged, of the finger for the binder.

The lay A³, longitudinally slotted at 10, Fig. 1, for the staff of the picker P, the shuttle-box, comprising the front wall B, back wall or plate B', and overhanging guard or cover plate B², the binder B^X, pivotally mounted 40 on a stud b^X, and the protector-shaft m, its

controlling-spring S, Fig. 2, and the arm m², having an upturned extension m³ bearing 50 against the binder, may be and are all of well-known construction and operate in the usual manner.

The cover-plate B² usually conceals and overhangs the inner free end of the binder to 55 such an extent that it is practically impossible for the attendant to take hold of and retract the binder when pushing the shuttle home in the box prior to starting the loom. Consequently the inner end of the shuttle 60 must be grasped, and by main force the attendant pushes the shuttle in against the resistance offered by the spring S, acting through the binder.

In my present invention I have provided 65 means whereby the attendant can readily retract the binder with one hand while inserting the shuttle with the other, and to this end I provide the binder with an upturned finger f, secured to its outer face and near its inner 70 or free end, the finger projecting far enough above the cover-plate B² to enable the operator to readily grasp it. Preferably the finger is made of metal, cast in the form shown clearly in Fig. 3, the finger being connected 75 by an offset portion f' with the flat body f^X, the latter resting against the back of the binder and being secured thereto by suitable screws 8, Fig. 2. A transverse rib f² is shown on the body, said rib entering a seat or recess 80 20, (see Fig. 1,) made in the binder to aid in retaining the finger in proper position. The offset f' prevents engagement of the finger with the cover-plate when the binder is in its extreme inner position. The attendant 85 grasps the finger f and forces the binder back when the shuttle is to be pushed back into the box, the retraction of the binder being readily accomplished with the expenditure of little force, while the shuttle can be easily 90 pushed into place, facilitating and making easier the work of the operative.

Having fully described my invention, what I claim as new, and desire to secure by Letters Patent, is—

In a loom, the lay, a shuttle-box thereon, a

spring-controlled binder, and an upturned finger secured to the outer face of the binder and offset therefrom, said finger projecting above the shuttle-box and behind the cover-
plate thereof, to permit ready manual retraction of the binder.

5 In testimony whereof I have signed my

name to this specification in the presence of two subscribing witnesses.

EDWARD S. STIMPSON.
